TOY ROCKET

Vern R. Gersmehl, Sr., Cheyenne, Wyo.

Application June 20, 1950, Serial No. 169,223

3 Claims. (Cl. 273—106.5)

1

This invention relates to toys of the airborne type, and in particular a projectile in the form of a rocket having resilient projecting means therein and a stand in which the projectile is removably held whereby with the projectile temporarily held in the stand and an elastic element drawn rearwardly and released the force of the impact shoots the projectile from the stand into the air.

The purpose of this invention is to provide a toy rocket that is self propelling and that may readily be shot from a stand or the like.

Various types of propelling means have been provided for toys and particularly for different types of aircraft but owing to the popularity of the rocket ships it has been found desirable to provide a toy that may be shot into the air. With this thought in mind this invention contemplates an elongated tubular projectile having a resilient element therein with the resilient element secured in the forward end of the projectile and having a knob positioned to extend from the rear whereby the knob may be drawn rearwardly and released to provide the propelling means for the projectile.

The object of this invention is, therefore, to provide means for forming a toy in the form of a rocket and whereby the toy may be shot through the air by propelling means incorporated therein.

Another object of the invention is to provide a toy projectile of the rocket type that may be reused.

Another object of the invention is to provide a combination of a toy projectile and stand whereby the projectile may be discharged from the stand with its own power.

A further object of the invention is to provide a toy rocket which is of a comparatively simple and economical construction.

With these and other objects and advantages in view the invention embodies an elongated tubular body having a pointed nose with a plug providing a bumper positioned in the rear end and with a resilient element secured in a bushing in the forward end and provided with a gripping knob on the rear end positioned to impact the plug.

Other features and advantages of the invention will appear from the following description taken in connection with the drawings wherein:

Figure 1 is a side elevational view illustrating the toy rocket positioned in the stand.

Figure 2 is a plan view of the rocket also showing the rocket positioned in the stand.

Figure 3 is an end elevational view looking to-

2

ward the forward end of the rocket and stand.

Figure 4 is a longitudinal section through the rocket taken on line 4—4 of Figure 2.

Figure 5 is a cross section through the forward end of the rocket taken on line 5—5 of Figure 4.

Figure 6 is a detail showing a modification wherein a tubular element formed of rubber is used as the propelling element instead of a spring.

Figure 7 is a view showing a further modification wherein the rocket is formed of rubber having a solid nose with an elastic shaft of reduced diameter.

Figure 8 is a cross section through the rocket shown in Figure 7 taken on line 8—8 thereof.

Referring now to the drawings wherein like reference characters denote corresponding parts the toy rocket of this invention is formed with a tubular body 10, having a nose 11 with a plug 12 in the rear end and with a coil spring 13 secured in the forward end by a bushing 14 and having a knob 15 on the opposite end.

A projectile is provided with a pin 16 that extends through the bushing 14 and the ends of the pin are positioned in sockets 17 and 18 in bearing elements 19 and 20 of posts 21 and 22, respectively. The posts are mounted on a stand 23 and the upper parts of the posts are held in spaced relation by a brace 24.

With the pin 16 extended through the body of the projectile or rocket and positioned with the ends in the sockets 17 and 18 a forwardly exerted force will shoot the projectile forward with the ends of the pin leaving the sockets.

The tubular body 10 of the projectile or rocket is formed with its greatest width at the point 25 and from this point the wall converges to the nose 11 and the rear portion also tapers to a smaller diameter at the rear end in which the plug 12 is positioned. The outer surface of the rear portion of the rocket is provided with fins 26 that extend radially outward as illustrated in Figure 3.

The forward end of the spring 13 is mounted on the pin 16 and the opposite end is mounted on a pin 27 extended through the knob 15 as shown in Figure 4. The spring extends through an opening 28 in the plug 12 and with the spring drawn rearwardly by the knob 15 to the position shown in dotted lines in Figure 4 and then released the force of the spring snaps the forward end of the knob against the surface of the plug 12 thereby shooting the projectile or rocket forwardly.

The tubular body 10 may be made of thin plastic, paper, or any suitable material and the nose 11 is secured on the forward end of the bushing

14 by an adhesive, such as cement, or the like and an annular groove 29 may be provided in the bushing to facilitate fastening the nose thereto. The bushing is provided with centrally disposed openings 30 in which the end of the spring 13 is positioned.

In the design illustrated in Figure 6 the spring is replaced by a rubber tube 31 and the forward end is held on a pin 32 similar to the pin 16 in a bushing 33 similar to the bushing 14. The opposite end of the tube is provided with a knob 34 similar to the knob 15 and the tube is secured in the knob by a pin 35.

In the design illustrated in Figures 7 and 8 the rocket is provided with a solid rubber nose 36 with a pin 37 extended therethrough and an elastic strip 38 extends from the nose to a knob 39 that is secured on the outer end of the strip by a pin 40. This unit is inserted in the tubular body 10 with the forward end of the tubular body mounted on the shoulder 41 at the rear end of the nose 36. In this design the outer shell is indicated by the numeral 42.

With the parts arranged in this manner the rocket is positioned in the stand, as illustrated in Figures 1, 2, and 3 and with the stand held in one hand the knob 15 is drawn rearwardly with the other and upon release of the knob it is drawn forwardly by the spring 13 to engage or impact the end of the plug 12 and the force of the impact drives the rocket or projectile forwardly through the air.

It will be understood that modifications may be made in the design and arrangement of the parts without departing from the spirit of the invention.

What is claimed is:

1. A toy rocket comprising a tubular body having a pointed nose and an open blunt rear end,

a bushing in said body adjacent the said pointed nose, a pin extending through said bushing transversely thereof and each end of said pin projecting outwardly of the body, a plug having a longitudinally extending bore and an enlarged impact portion positioned in the open blunt end of said body, a resilient element positioned in said body with one end fixed to said pin and the other end extending outwardly of the body through the bore in said plug, a knob on the last said end having an impact portion thereon adapted to engage the impact portion of said plug and said resilient element is adapted to be extended beyond the end of said plug by means of manual operation of said knob so that when said knob is released the impact portion thereon will forcibly engage the impact portion on the plug to drive the body forward.

2. A toy rocket as in claim 1 wherein a stand is provided for releasably holding the said body by means of the ends of the pin extending outwardly of the said body.

3. A toy rocket as in claim 1 wherein radially disposed fins are positioned on the exterior surface of the body adjacent the open blunt end thereof.

VERN R. GERSMEHL, SR.
